ISOMERIZATION OF HYDROCARBONS

Bertrand W. Greenwald, Haddonfield, and Daniel Milsom, Hightstown, N.J., assignors to Cities Service Research and Development Company, New York, N.Y., a corporation of New Jersey

Filed Aug. 29, 1958, Ser. No. 758,105

5 Claims. (Cl. 204—162)

This invention relates to the catalytic isomerization of light hydrocarbons and is more particularly directed to the production of isomeric C_4 — C_7 hydrocarbons from corresponding normal hydrocarbons and mixtures of the same in the presence of an irradiated catalyst.

In recent years there has been an increasing demand for C_4 , C_5 and C_6 isomers, particularly the C_4 and C_5 isomers. These compounds are particularly useful in upgrading gasolene to octane ratings that meet the continuously increasing requirements of high compression internal combustion engines.

Isomerization, both in the liquid and vapor phase, has been obtained by several commercially acceptable methods. One of the early commercial methods utilized metal salts of the Friedel-Crafts type. More recently the vapor phase isomerization of C_4 and C_5 hydrocarbons has been carried out over a fixed bed of dual function catalysts such as molybdenum on silica-alumina or nickel on silica-alumina. Still more recently an improved isomerization process has been adopted which utilizes a noble metal such as platinum or palladium on a suitable catalyst base. Both of the foregoing isomerization reactions using either the molybdenum type or the noble metal type have serious shortcomings. For example, the molybdenum containing catalysts have high coke forming characteristics and therefore require frequent regeneration. The noble metal type catalysts, while having a low coke forming rate, must be used at comparatively high pressures, in the neighborhood of 900 lbs. per sq. inch, and temperatures in a range of from about 700° F. to 1000° F. to provide satisfactory conversion rates. While such processes have been and are being commercially used for the isomerization of light naphthas as well as C_4 and C_5 hydrocarbons, no isomerization process is presently available which will economically convert C_6 and/or C_7 hydrocarbons to their respective isomers.

It has now been found quite unexpectedly according to the present invention that substantial yields of isomeric hydrocarbons can be obtained from normal hydrocarbons, including in particular heptane, by utilizing an isomerization catalyst of the platinum or molybdenum type which has been subjected to specific amounts of gamma radiation.

Quite contrary to present techniques high yields of isomerized hydrocarbons, including iso-heptanes, are now obtainable at atmospheric pressure and temperatures considerably lower than the temperatures utilized in existing processes. When isomerization is carried out under the conditions hereinafter described at conventional space velocities with catalysts particularly treated in the manner described, a six fold increase in isomeric product may be obtained. In addition to increasing the product yield, the isomerization process of the present invention is far more selective than presently available isomerization processes.

It is therefore an object of the present invention to more effectively isomerize hydrocarbons.

It is a further object of the present invention to isomerize normal hydrocarbons over a standard isomerization catalyst which has been subjected to gamma radiation.

It is a further object of the present invention to convert normal hydrocarbons, in particular heptane to iso-

2

heptanes, at lower pressures and temperatures than was heretofore possible.

It is a still further object of the present invention to convert normal heptane to iso-heptane with less cracking and at a higher conversion ratio than it has heretofore been possible by any known isomerization method.

These and other objects and advantages will be more apparent from the description which follows.

FIGURE 1 is a plot of the effect of pre-irradiation of catalyst used in the conversion of n-heptane to iso-heptanes.

FIGURE 2 shows a comparison between irradiated and unirradiated catalysts in a conversion of n-heptane to iso-heptanes.

The present invention viewed in its broadest aspect is directed to a process for isomerizing light hydrocarbons at atmospheric pressure at temperatures in the range of from about 600° F. to 750° F. by means of an isomerization catalyst which has been subjected to sufficient gamma radiation to provide the catalyst with a total dosage of at least 1.7×10^7 roentgens.

While the process of the present invention is generally applicable to the isomerization of any saturated hydrocarbon, it is especially suited for the isomerization of n-butane, n-pentane, n-hexane and n-heptane. These hydrocarbons may be used as individual compounds in a relatively pure state. Mixtures such as the butane-butylene and pentane-ethylene fractions from which unsaturated hydrocarbons have been removed may also be utilized.

The isomerization of these various saturated hydrocarbons is accomplished according to the method of the present invention by means of irradiated isomerization catalysts. Thus the isomerization is effected by contacting the light hydrocarbon, either in a vapor, liquid or mixed phase, with the selected catalyst properly irradiated under the isomerization conditions described hereinafter.

It has been found that standard isomerization catalysts of the molybdenum or platinum type on a suitable carrier such as alumina or silica-alumina, either with or without an active metal promoter, when exposed to gamma radiation of sufficient intensity and for a period of time sufficient to provide a total dosage of from 1.7×10^7 to 1.3×10^8 roentgens an unusually high conversion rate to the isomeric form will result.

The exact reason for this unexpected result is not clear, though it appears that the catalyst is activated to a high energy level which makes it a far more effective isomerization material.

The irradiation of the catalyst to the extent desired may be accomplished in a number of ways. The catalyst may be pre-irradiated prior to use in the reaction vessel by subjecting the same to irradiation of sufficient intensity prior to placing the catalyst in the reactor. If desired,

however, the catalyst may be irradiated in situ in the reaction vessel by providing a reaction vessel of such design that suitable radiation sources may be placed therein to influence the catalyst in place. When such a technique is used, some advantage in convenience of handling results, particularly when regeneration of the catalyst is required. It is to be noted that while the catalyst may be suitably irradiated in place, the presence of the gamma source in the reaction zone does not have any deleterious effect on either the hydrocarbon feed or the product resulting therefrom. If fresh catalyst is to be used for the isomerization of the platinum promoted type it may be necessary to first heat treat or soak the catalyst for a period of time, sufficient to minimize the cracking effect which would otherwise result.

The importance of providing the catalyst with a sufficient total dosage of gamma radiation in the range set

forth will be apparent from FIGURE 1 wherein the percent of conversion of n-heptane to iso-heptane is plotted against the total time of irradiation in hours at a dosage rate of 7×10^5 roentgens per hour. This plot resulted from a series of runs on a n-heptane feed at a temperature of 625° F. (± 25 ° F.) which appears to be about the optimum condition for the conversion of maximum amounts of iso-heptane at the total dosage shown. It will be noted that a total dosage amounting to 2.3×10^8 roentgens produced an adverse effect on the isomerization of n-heptane at the 625° F. temperature.

The isomerization may be carried out in either the vapor phase, liquid phase or in a mixed vapor-liquid phase as desired. Normally the lower boiling hydrocarbons are preferably isomerized in the vapor phase, whereas higher boiling hydrocarbons are isomerized in the liquid phase. It has been found that vapor phase isomerization of heptane according to the present method is most satisfactory. A fixed bed of catalyst in a suitable reactor which may be of a tubular or tray design can be used. The catalyst must of course be positioned in such a manner that maximum contact can be made between the feed and catalyst particles. This of course can be accomplished by flowing the feed through the catalyst particles in either a concurrent or countercurrent manner. The presence of a gamma irradiation source in the reaction zone during the isomerization reaction will not adversely affect either the feed or the product.

As has previously been indicated high pressures are generally required for isomerizing the higher normal hydrocarbons such as C₆ and C₇ when the promoted platinum type isomerization catalyst is used. However, one of the distinct advantages of the present process stems from the fact that the isomerization can be carried out effectively at atmospheric pressure. In a somewhat similar manner and in contrast to conventional techniques the temperature range suitable for the isomerization is from 600° F. to about 750° F. When a n-heptane feed is being isomerized and a catalyst having a total dosage of radiation in the range specified is being used, a temperature of between about 625° F. and 650° F. is most effective.

EXAMPLE

In an isomerization reaction carried out according to the method described above, the reaction system containing 100 ml. of platinum on alumina isomerization catalyst having a total dosage of 1.1×10^8 roentgens was first purged with nitrogen for approximately 30 minutes, followed by hydrogen gas for 3 hours. Liquid heptane was then pumped into the reaction zone at a rate of 58 ml. per hour together with sufficient hydrogen gas to provide a mole ratio of hydrogen to heptane of 4:1. The temperature of the bed was maintained at 625° F. The product after 40 minutes was collected and discarded, including the product in the cold traps. Heptane and hydrogen were continued through the reaction zone for an additional hour during which time the liquid products from the ice water trap, the Dry-Ice acetone trap and the liquid nitrogen traps were combined and weighed. The exit gas, primarily hydrogen, was measured by means of a wet test meter. The exit gas and liquid isomerate were analyzed by vapor phase chromatography. The exit gas showed traces of methane and ethane. The liquid sample analyzed as shown in Table I for the run is identified as No. 2.

The importance of the finding that irradiated isomerization catalyst provides a substantial improvement over existing isomerization processes will be more readily apparent from a review of Table I which follows.

TABLE I
Effect of radiation on conversion to heptane isomers

Run No.	Catalyst History	Conversion, Weight percent	Selectivity ¹	Conversion to i-C ₇ Weight percent	i-C ₇ 's R, i-C ₇ 's Base
10	Three Regenerations.	12.3	34.9	4.3	
	Four Regenerations, 1.1×10^8 R.	32.5	79.0	25.6	5.98
	Heat Soaked—168 hrs.	5.9	100	5.9	
	Heat Soaked—336 hrs, 1.2×10^8 R.	39.9	89.0	35.5	6.01

¹ Selectivity = $\frac{\text{Fraction converted to i-C}_7 \times 100}{\text{Total Conversion}}$

In the foregoing table all runs were made on the same catalyst at 625° F. in the system described in the example. In run No. 1 the catalyst was not subjected to gamma radiation but had been subjected to three regenerations as indicated. It will be noted that the total conversion of feed which was n-heptane amounted to 12.3% with 34.9% of this value representing iso-heptane. In run No. 2 the catalyst had four regenerations and was subjected to a total dosage of gamma radiation of 1.1×10^8 roentgens; total conversion amounted to 32.5% of which 79% represented iso-heptane. The latter represent a 5.9 fold increase in the amount of iso-heptane recovered. In a similar manner another portion of the same catalyst was first heat soaked for a period of 168 hours as shown for run No. 3 to reduce the cracking tendency of the catalyst. Total conversion using this sample at 625° F. amounted to about 5% with this value representing the total amount of iso-heptane recovered. In run No. 4 the catalyst was further heat soaked and subjected to gamma radiation to provide a total dosage thereon of 1.2×10^8 roentgens as shown. Isomerized heptane obtained amounted to 89% by weight of the total 39.9% of the n-heptane converted. As shown in the ratio column at the far right of Table I the irradiated catalyst produced a six fold increase in isomerate.

The substantial improvement, particularly in the isomerization of heptane according to the method utilized herein, is graphically shown in FIGURE 2. In this figure a comparison between an unirradiated and an irradiated catalyst is graphically provided. It will be noted that the irradiated catalyst resulted in a 12.6% conversion to iso-heptane, whereas the unirradiated catalyst at the same temperature produced a 4.3% conversion to iso-heptane.

When isomerization is carried out under the conditions specified, the catalyst treated in the manner described according to the process of the present invention is extremely selective. This will be apparent from Table II wherein analytical data is set forth on a series of runs carried out over a temperature range of from 600° F. to 800° F.

TABLE II
Analytical data on isomerates

Run No.	°F.	Weight percent C ₃	i-C ₄	n-C ₄	Total i-C ₇ 's	Total Conversion	Selectivity ¹
70	600	Trace	Trace	Trace	3.7	3.7	100
	600R	Trace	Trace	Trace	4.4	4.4	100
	650	5.1	4.3	3.0	4.3	16.6	25.9
	650R	0.5	0.9	0.6	12.6	14.6	86

	800R	(7.0)	(6.9)	(7.1)	1.8	22.8	8

¹ See definition under Table I.

² Corrected to 90% overall balance.

In the table the letter R following a temperature indicates that the catalyst was irradiated. It will be noted that excellent selectivity was obtained on a n-heptane feed over the range of from about 600° F. to 650° F.

As in conventional isomerization processes the catalyst of the present invention will after a series of runs require regeneration. The period during which the catalyst may be kept on stream with the regeneration will depend on several factors, including the type of feed, temperature and particular catalyst used. Regeneration may be carried out in situ as accomplished in conventional isomerization processes with air being used to remove undesirable coke laid down. Since regeneration apparently has no measurable effect on the high level of energy induced by the gamma radiation it will not be necessary to subject the catalyst to an irradiation source during each regeneration, in fact if the catalyst is subjected to the gamma source during isomerization the catalyst may be regenerated many times without being subjected to further dosage to insure maximum effectiveness. If the catalyst is pre-irradiated prior to being inserted in the reaction vessel it may be desirable after a series of regenerations to re-irradiate the catalyst by subjecting the same to further gamma radiation. This can be accomplished by withdrawing the catalyst from the reaction zone, irradiating the same externally of the reactor and thereafter returning the treated catalyst to the reaction zone.

While the foregoing process has been described with some particular reference to the isomerization of heptane it is to be understood that the invention is not limited thereto, but may be used for other low molecular weight hydrocarbon feeds in a vapor, mixed or liquid phase process. The particular example cited in which heptane served as the feed is considered to be illustrative of the invention and is not to be construed as limiting the same. The only limitations to be imposed on this invention are those contained in the claims appended hereto.

We claim:

1. In a process for the isomerization of normal saturated C₄-C₇ hydrocarbons, the improvement which comprises contacting a vaporous feed of normal C₄-C₇ hydrocarbons in a reaction zone, maintained at a temperature of between 600-700° F., with an isomerization catalyst of the platinum and molybdenum types which has been subjected to sufficient gamma radiation to provide the catalyst with a total dosage of from 1.7×10⁷ to 1.3×10⁸ roentgens.

- 5 2. In a process for the isomerization of an isomerizable saturated C₄-C₇ hydrocarbon, the improvement which comprises contacting the hydrocarbon in a reaction zone, maintained at a temperature of between 600-750° F., with an isomerization catalyst of the platinum and molybdenum types, said catalyst having been subjected to sufficient gamma radiation to maintain a total dosage of from 1.7×10⁷ to 1.3×10⁸ roentgens and withdrawing and separating an isomerized product.
- 10 3. In a process for isomerizing normal heptane to iso-heptane, the improvement which comprises contacting normal vaporous heptane with an isomerization catalyst of the platinum and molybdenum type in a reaction zone, maintained at a temperature of about 600-750° F., said catalyst having been treated with sufficient gamma radiation to provide the catalyst with a total radiation dosage of from 1.7×10⁷ to 1.3×10⁸ roentgens, and withdrawing an iso-heptane product.
- 15 4. In a process for the isomerization of an isomerizable saturated C₄-C₇ hydrocarbon, the improvement which comprises contacting the hydrocarbon with a noble metal containing isomerization catalyst in a reaction zone maintained at a temperature of from 600-750° F., said catalyst prior to its introduction into the reaction zone having been treated with sufficient gamma radiation to provide the catalyst with a total dosage of from 1.7×10⁷ to 1.3×10⁸ roentgens, and withdrawing and recovering an isomerized hydrocarbon product.
- 20 5. In a process for the isomerization of heptane, the improvement which comprises contacting heptane with a noble metal containing isomerization catalyst in a reaction zone maintained at a temperature of from 600-750° F., said catalyst having been subjected to sufficient gamma radiation to provide the catalyst with a total gamma radiation dosage of from 1.7×10⁷ to 1.3×10⁸ roentgens, withdrawing and recovering an iso-heptane product and periodically regenerating said catalyst.
